[57] ABSTRACT

A V-blade plow having a pair of adjustable plow blades. Each plow blade has an inner end pivoted on a central pivot assembly. A plowed material catcher member is mounted below the central pivot assembly to prevent a trail of snow from passing through any space between the inner ends of the blades at any position of blade adjustment. The plowed material catcher member includes an arcuate ramp portion which projects forwardly of the central pivot assembly and directs snow to the blades respectively. The catcher member is made from a material selected from rubber, plastic or metal.

PLOWED MATERIAL CATCHER FOR V-BLADE SNOWPLOW

REFERENCE TO RELATED APPLICATION

This invention is the subject of provisional application Ser. No. 60/087,070 filed May 28, 1998 and entitled SNOW CATCHER.

BACKGROUND AND BRIEF DESCRIPTION OF THE INVENTION

The present invention provides a plowed material catcher attachment system for an adjustable V-bladed snowplow or other V-bladed plow.

The prior art uses flat rubber belting bolted to the cutting edges of the blades to prevent a small trail of plowed material from passing through the blades.

The object of the invention is to provide an adjustable V-bladed plow with a device to prevent the small trail of material which passes through the small opening between two blades in any blade position.

A plowed material (e.g. snow) catcher member is fixedly mounted below the center or vertical pivot assembly for the adjustable blades. It includes an arcuate ramp portion projecting forwardly of the central pivot assembly and directs plowed material to the blades, respectively.

Reference is made to Capra et al, U.S. Pat. No. 5,568,694 (incorporated herein by reference) for a full exposition of the plow and its functioning operation.

DESCRIPTION OF THE DRAWINGS

The above and other objects, advantages and features of the invention will become more clear when considered with the following specification and accompanying drawings wherein;

FIG. 1 is an exploded view of a snow plow system incorporating the invention,

FIG. 2 is an enlarged isometric view of the snow catcher of this invention,

FIG. 3 is an enlarged view of the snow catcher per se, and

FIG. 4 is a sectional view of the snow catcher.

DETAILED DESCRIPTION OF THE INVENTION

Referring to FIG. 1, the following list sets out the component part number and description of the component part:

Component Part	Description
1	Blade Half Right
2	Blade Half Left
3	Center Section, RT3 V-Blade (all models)
4	T-Frame, RT3 V-Blade (all models)
5	Cutting Edge, 7'6" V-Blade $\frac{5}{8}$ " Holes
5	Cutting Edge, 8'2" V-Blade $\frac{5}{8}$ " Holes
5	Cutting Edge, 9'2" V-Blade $\frac{5}{8}$ " Holes
6	Carriage Bolt Set
	Includes:
	(10) Carriage Bolts $\frac{5}{8}$ "-11 x 2" Grade #5 ZN
	(10) $\frac{5}{8}$ " Hardened Washers
	(10) $\frac{5}{8}$ " Lock Nuts
7	Bumper Stop, w/Mounting Hardware
7	A Self-Tapping Bolt, $\frac{3}{8}$ "-16 x 2" Hex Washer Head ZN
9	Spring Yoke, RT3 V-Blade
10-44-45	Plow Shoe Assembly

-continued

Component Part	Description
5	Includes:
10 10-44-45	(1) Plow Shoe (1" Shaft) (1) $\frac{1}{16}$ " Quick Pin (20) 1" Flat Washers Plow Shoe, Cast Iron (Center Shoe) Includes:
15 11	(1) Plow Shoe (1" Shaft), Cast Iron
12	(1) $\frac{1}{16}$ " Quick Pin
13	(20) 1" Flat Washers
14	Snow Catcher w/Mounting Hardware
14 A	Horizontal Hinge Pin Kit, RT3 V-Blade (all models)
14 B	Center Hinge Pin, RT3 V-Blade (all models)
14 C	Hydraulic Pump - Power Unit Barnes
14 D	Hydraulic Pump Filter Cap
14 E	Hydraulic Pump Motor-Barnes
14 F	Hydraulic Pump Solenoid
14 G	Hydraulic Pump Solenoid Ground Cable
14 H	Battery cable, 66"
14 J	Ground/Power Cable 60" (Vehicle Side)
14 K	Ground/Power Cable 36" (Plow Side)
14 L	Ground/Power Cable Dust Cap/Plug
15	Hydraulic Reservoir Drain plug
15 A	Hydraulic Valve Assembly with SmartHitch
15 B	Hydraulic Lift/Angle Valve
15 C	Hydraulic Valve Coil
15 D	Hydraulic Relief Valve
15 E	Hydraulic Check Valve
30 15 F	Hydraulic Valve Screen Cartridge
15 G	Hydraulic Valve Ground Strap
15 H	Hydraulic Valve, SmartHitch Attach
16	Hydraulic Valve, Flow Control Cartridge
35 17	SmartHitch Toggle Switch Kit (Includes Switch and Jumpers)
18 A	Hydraulic Cylinder, Angle
18 B	Hydraulic Hose $\frac{1}{4}$ " x 12", $\frac{1}{4}$ " MNPT x $\frac{1}{4}$ " MNPT
18 C	Hydraulic Hose $\frac{1}{4}$ " x 15 1/2", ($\frac{1}{4}$ " MNPT x $\frac{1}{4}$ " MNPT)
22	Hydraulic Hose $\frac{3}{8}$ " x 40" ($\frac{1}{4}$ " MNPT x $\frac{3}{8}$ " MNPT)
25	Hydraulic Cylinder, RT3 Lift
40 32	Hydraulic Swivel Fitting, 90 Deg. ($\frac{1}{4}$ " ORS x $\frac{1}{4}$ " FPS)
33	Trip/Return Spring
37	Blade Guide Set
37 A	Blade Guide Tip
38	Auxiliary Headlight Set, Low Profile Plastic
38 A	Turn Signal Cover, Low Profile Plastic
38 L	Auxiliary Headlight, Left, Low Profile Plastic
38 R	Auxiliary Headlight, Right, Low Profile Plastic
39	Auxiliary Light Harness Assembly
39 A	Includes: Toggle Switch Connectors
39 B	Light and Control Harness 116" (Vehicle Side)
50 40 A	Light and Control Harness 48" (Plow Side)
40 B	Switch Box Control, V-Blade
41	Joystick Control, V-Blade
42	Rocker Switch - Lift
	Rocker Switch - Angle
	Quick Pin - $\frac{1}{16}$ "
	Hydraulic Fitting, 90 Deg. ($\frac{1}{8}$ " MNPT x $\frac{1}{4}$ " FNPT)
55 47	Eye Bolt, $\frac{1}{2}$ "
55	Hex Head Cap Screw, $\frac{5}{8}$ "-11 x 4 1/2" GRS ZN
	Pivot Pin, Kit (Includes Cotter Pins and Washers)
	Pivot Pin
	$\frac{1}{16}$ " Cotter Pin
	Coupler Assembly
	Push Beam Assembly, RT 3
	Push Beam Support Plat RH (Passenger Side)
	Push Beam Support Plate LH (Driver Side)
	Coupler Spring Pin Kit
	Includes:
60	Coupler Spring Pin
	Rolled Pin
	Coupler Spring Pin Spring

-continued

Component Part	Description
64 A	Coupler Spring Pin
64 B	Rolled Pin (3/16" x 20 1/2")
64 C	Coupler Spring Pin Spring
67	Spring, SmartHitch Torsion Spring
71	Washer, 3/8" Split Lock
72	Washer, 3/8" Fender
73	Light Bracket Assembly
73 A	Hydraulic Enclosure Cover
73 B	Rubber Grommet
73 C	Thumb Screw, 10-24 x 1/2"
75 A	Angle Bracket RH (Passenger Side)
75 B	Angle Bracket LH (Driver Side)
80	Control Harness Mounting Bracket
85	Hairpin Cotter, #16
86	Clevis Pin, 5/8" x 3 1/2"
96	Hex Head Cap Screw, 5/8"-11 x 5 1/2" GR5 ZN
97	Nut, Self-Locking 5/8" - 11 ZN
101	Power Ground Cable Mounting Bracket
102	Rubber Split Grommet, 1 1/8"
104	Weather Cap for Light & Control Harness (Vehicle Side)
106	Weather Cap for Light & Control Harness (Plow Side)
108	Headlight Adapter Kit

As shown in FIG. 1, the blades 1 and 2 of the plow are pivotally mounted on a center section 3 having a center hinge pin 13 and the angle of the blades 1 and 2 is adjusted by hydraulic cylinders 17. The invention features a plowed material catcher 11 which is fixedly mounted on the lower end of center section 3 and hinge pin 13. Plowed material catcher 11 has a ramped surface 11R which is arcuate and generally conically shaped and, in a preferred embodiment, makes an angle of about 120°-130° to the plowed surface—123.7° in the preferred embodiment. As shown in FIG. 2, the conically shaped ramp surface 11R is located behind the

bottom edge of the adjustable blades 1 (The other adjustable blade 2 is removed for clarity in FIG. 2.) and closes the opening in the middle of the two blades in all positions of blade adjustment. Plowed material catcher 11 may be molded or machined from rubber, plastic or steel. The catcher 11 has a flat upper surface 11F and mounting hole 11MH. Raised portion 11P includes a key hole 11K for receiving a key pin (not shown) which prevents rotation of catcher 11.

In operation, any plowed or unplowed material which would tend to trail between the blades is blocked and directed to the plowed material catcher 11 to one blade or the other so as to not leave a trail of plowed material between the plow blades 1 and 2.

While the invention has been described in relation to preferred embodiments of the invention, it will be appreciated that other embodiments, adaptations and modifications of the invention will be apparent to those skilled in the art.

What is claimed is:

1. In a V-blade plow having a pair of adjustable plow blades having inner ends hinged on a central pivot assembly and having bottom edges, the improvement comprising a plowed material catcher member mounted below said central pivot assembly said catcher member having a conically shaped ramp surface and positioned behind said bottom edges to prevent a trail of plowed material from passing through any space between the inner ends of said blades at any position of blade adjustment.

2. The invention defined in claim 1 wherein said conically shaped ramp surface portion makes an angle of about 120°-130° to a surface being plowed.
